UNITED STATES PATENT OFFICE.

WALTER S. COLES, OF CINCINNATI, OHIO.

DESIGN FOR A WHIST-TRAY.

SPECIFICATION forming part of Design No. 27,278, dated June 29, 1897.

Application filed April 19, 1897. Serial No. 632,871. Term of patent 14 years.

To all whom it may concern:

Be it known that I, WALTER S. COLES, a citizen of the United States, residing at Cincinnati, county of Hamilton, and State of Ohio, 5 have invented and produced a new and original Design for Whist-Trays, of which the following is a full, clear, and exact description, reference being had to the accompanying drawing, forming part of this specification.

10 In the drawing the figure is a perspective view of my whist-tray, showing my new design.

As shown in the drawing, the leading or material feature of the design consists of a square 15 tray or board A, provided with eight com-

partments or recesses for the reception of eight hands of whist of thirteen cards each, the compartments or recesses being arranged in pairs, any two consecutive pairs being at right angles to the others in the direction of their 20 length.

Having thus described my invention, what I claim as new, and desire to secure by Letters Patent, is—

The design for a whist-tray, substantially 25 as herein shown and described.

WALTER S. COLES.
